(57) **CLAIM**

The ornamental design for an extra-large cantilever mount for a flat panel display, as shown and described.

DESCRIPTION

FIG. 1 is a top, right isometric view of an embodiment of an extra-large cantilever mount for a flat panel display showing our design.

FIG. 2 is a front elevational view thereof.

FIG. 3 is a rear elevational view thereof.

FIG. 4 is a right-side elevational view thereof; the left-side elevational view is a mirror image of FIG. 4; and,

FIG. 5 is a top plan view thereof; the bottom plan view is a mirror image of FIG. 5.

Elements identified in broken lines in the accompanying drawings form no part of the claimed invention.
